UNITED STATES PATENT OFFICE.

NICOLAS PIEPER, OF LIEGE, BELGIUM.

AUTOMATIC PISTOL.

1,427,413.

Specification of Letters Patent. Patented Aug. 29, 1922.

Application filed July 8, 1919. Serial No. 309,443.

(GRANTED UNDER THE PROVISIONS OF THE ACT OF MARCH 3, 1921, 41 STAT. L., 1813.)

To all whom it may concern:

Be it known that I, NICOLAS PIEPER, a subject of the King of Belgium, 5-7 Rue Bonne-Nouvelle, in Liege, Belgium, have invented 5 certain new Improvements in Automatic Pistols (for which I have filed applications in Belgium, Dec. 27, 1913; France, June 6, 1914; Spain, June 15, 1914; Austria, July 16, 1914; Hungary, July 16, 1914; Germany, 10 June 22, 1914; Holland, Feb. 23, 1916; Great Britain, May 27, 1919), of which the following is a clear and exact description.

The subject of this invention is an automatic pistol which can be taken to pieces, 15 comprising a barrel completely distinct and independent from the receiver, which forms part of the stock.

The accompanying drawing shows, by way of example, three alternative arrangements 20 of such a pistol:

Figure 1 is a longitudinal section of the first arrangement;

Figure 2 is a cross section through A—A (Figure 1);

Figure 3 is a section through B—B (Figure 1);

Figure 4 is an outside view of the pistol;

Figure 5 is an elevation view of the stock alone;

Figure 6 shows a longitudinal section of the second arrangement;

Figure 7 is a section through C—C (Figure 6);

Figure 8 is a section through D—D (Figure 6);

Figure 9 is an outside view of the pistol;

Figure 10 is a longitudinal section of the third arrangement;

Figure 11 is a front view of the barrel.

The arm consists of the stock 1, the rear top part of which 2 forms the receiver, in which the bolt 3 works in the well known manner. This bolt 3 contains the firing pin 4, acted upon by a spring 5, which rests at 45 its other end on the bottom of the receiver 2 or rear wall of stock 1.

The barrel 6 presents at its lower part the two brackets 7 and 8, through which it is secured on the stock 1. In the example 50 shown, the rear bracket 7 engages on a fixed pin 9, whereas the front bracket 8 seizes the

front edge of the stock 1; this bracket 8 provides also a housing for a locker 10 which partly engages in the stock 1 and thus prevents any longitudinal displacement of the 55 barrel 6.

The barrel 6 is surmounted by a chamber 11 containing the bolt-return spring 12, which rests at the rear on the back wall 13 of this chamber 12, and in front on the head of 60 the rod 14 which passes through the back wall 13 and is secured to the bolt 3. In the arrangement shown, the rod 14 is screwed in a lug 15 provided on the bolt 3, which lug 65 can travel backward and forward in the upper part of the receiver 2.

The receiver 2 is provided with longitudinally extending slots 16 and slidably mounted in these slots are longitudinally extending members 17 connected together at their forward ends and in advance of the bolt 15 by a cross piece, this cross piece being perforated for the passage of rod 14. The members 17 are connected together at their rear ends by a U-shaped piece or stock 18, the 70 ends of which are pivotally connected to members 17 so that it may be swung upwardly to disengage the rear wall of the receiver to permit the barrel and bolt to be removed together, that is without unscrewing the rod 14. The side surfaces of the U-shaped piece 18 are ribbed or knurled so that this member may be firmly gripped by the fingers to work the bolt by hand to cock the 75 pistol preparatory to firing the first shot. 80

To take the arm to pieces, it is therefore only necessary to raise the stirrup 18, release the locker 10 by pushing it upwards and pull the barrel towards the front.

The arrangement of the arm shown in 90 Figures 6 to 9 is similar to the above. In it the receiver also forms part of the stock 1, whilst the barrel 6 surmounted by the chamber 11 of the return spring 12 is simply applied against the front face of the said receiver and fixed on the front part of the 95 stock 1.

The bolt 3 is, as in the foregoing example, secured to the rod 14 of the return spring 12; it consists of a cylindrical piece 100 the length of which corresponds to that of the stock and which carries on its sides the

two projections 19 which slide in the lateral slots 16 of the receiver 2 and enable the arm to be worked by hand.

The bolt 3 contains the firing pin 4, the spring 5 of which rests at the rear on a part 20 of the receiver 2. This part 20 is surrounded by the bolt 3 which is grooved or slotted longitudinally at its lower part (Figures 6 and 7).

10 The detent mechanism may be of any convenient type; in the example shown, it consists of a tumbler 21 which is acted upon by the rod 22 of the trigger 24. The rear end of the rod 22 meets the inclined face 23 of the stock 1 when the trigger is pulled, which brings about the release of tumbler 21 from rod 22, and prevents continued discharge of the pistol.

In the case of Figures 6 to 9, the barrel 6 also presents underneath the two lugs 7 and 8; the rear lug 7 engages with a fixed pin 9, whilst the front lug 8 is crossed by a screw 27 provided, for the sake of facilitating the dismantling and assembling, with a lever 25 easily worked by hand.

The ejector consists of a rod 25 slidably mounted in a tubular recess in the forward end of the bolt 3, this recess being inclined to the axis of the bore and open at both ends. 30 The forward end of rod 25 lies immediately in rear of one edge of a cartridge shell when in position to be fired and its rear end is positioned to strike member 26 when the bolt is in its rearward position. When the bolt 3 is pulled back, this latter end comes in contact with the face 26 of slot 16 in stock 1, thereby causing the cartridge case to be pivoted and ejected through the slot 16 opposite.

40 In the arrangement shown in Figures 10 and 11, the bolt-return spring 12 is housed in the receiver 2 above the bolt 3 and behind the lug above the said bolt. In this alternative arrangement, the barrel 6 is no longer surmounted by the chamber 11 but by a mere strip 28 of reduced width.

The barrel 6 which is applied against the front face of the receiver 2 is secured to the stock 1 by a similar arrangement to those 50 previously described, which permits of the pistol being easily taken to pieces.

In order to prevent the bolt 3 from being thrust forward by the return spring after the barrel 6 has been removed, a locking device 29 is provided, which enables the bolt 3 to be locked on the stock 1, in the receiver 2, such locking device consisting, for instance, of a flattened or notched pin similar to the safety lock arrangement.

60 Having now particularly described and ascertained the nature of my said invention, and in what manner the same is to be performed, I declare that what I claim is:

1. In an automatic pistol, in combination,

a stock having a receiver therein for a reciprocable bolt, said receiver having an opening in its forward end for the insertion or withdrawal of the bolt and having longitudinal slots in its side walls, a barrel removably secured to said stock in advance of said receiver, a reciprocable bolt in said receiver, elements movable with said bolt and extending latterly through said longitudinal slots, and a locking member connected to one of said elements and adapted to engage the stock when the barrel is removed to prevent the escape of the bolt from the receiver, said member being manually movable relatively to said bolt and stock, to permit the bolt to be removed from said receiver.

2. In an automatic pistol in combination, a stock having a receiver therein for a reciprocable bolt, said receiver having an opening in its forward end for the insertion or withdrawal of the bolt and having longitudinal slots in its side walls, a barrel removably secured to said stock in advance of said receiver, a reciprocable bolt in said receiver, elements movable with said bolt and extending latterly through said longitudinal slots, and a locking member pivotally connected to each of said projecting elements and adapted to engage a portion of the stock to prevent the escape of the bolt from the receiver when the barrel is removed, said member being manually movable relatively to said bolt and stock to permit the bolt to be removed from said receiver.

3. In an automatic pistol in combination, a stock having a receiver therein for a reciprocable bolt, said receiver having an opening in its forward end for the insertion or withdrawal of the bolt and having longitudinal slots in its side walls, a barrel removably secured to said stock in advance of said receiver, a reciprocable bolt in said receiver, elements movable with said bolt and extending latterly through said longitudinal slots and a loop-shaped locking member pivotally connected to each of said elements and normally extending in rear of said stock to engage the same to prevent the escape of the bolt from the receiver when the barrel is removed, said member being manually movable from behind said stock to permit the bolt to be removed from said receiver.

4. In an automatic pistol, in combination, a stock having a receiver therein for a reciprocable bolt, said receiver having an opening in its forward end for the insertion or withdrawal of the bolt and longitudinal slots in its side walls, a reciprocable bolt in said receiver, and means passing through said slots and connected to said bolt for normally locking the same in said receiver, said means being movable to unlocking position to permit the removal of the bolt from the receiver.

5. In an automatic pistol, in combination,

a stock having a receiver therein for a reciprocable bolt, a reciprocable bolt in said receiver, a detachable barrel having a spring housing thereon, a return spring for said bolt positioned in said housing the rear end of said spring bearing against the end wall of the housing, and a rod connecting said bolt and spring, said rod having threaded

engagement with the bolt the barrel and the bolt being removable as a unit. 10

In testimony whereof I affix my signature in presence of two witnesses.

NICOLAS PIEPER.
